KEY HOLDER

Norbert Leopoldi, 4180 Marine Drive, Chicago, Ill.
Filed May 31, 1961, Ser. No. 113,863
1 Claim. (Cl. 70—459)

My invention relates to a holder for keys and the like, and more particularly, to a simplified holder for a plurality of keys that permits keys to be easily applied and removed, but which securely retains the keys thereon and permits ready use of them when needed.

Conventional key rings or holders generally permit one to readily use the keys applied thereto when needed, but frequently they are so arranged that it is difficult to secure keys thereto or remove keys therefrom. In most devices of this type, substantial pressure must be applied to either the key holder or the key to put the key on in place on the holder or remove a key therefrom. This not infrequently results in broken finger nails, bruised fingers and hands, and general irritation and inconvenience to the user.

The principal object of this invention is to provide not only a simplified key holder comprising a minimum of parts which securely holds keys that have been applied thereto, and which may be disassembled with a minimum of effort for removing keys therefrom or applying keys thereto, but also to provide a key holder arrangement of this type which employs a novel spinner device for effectively displaying advertising indicia.

A further object of the invention is to provide a key holder having a general configuration that lends itself to being easily grasped by the user.

Other objects, uses and advantages will be obvious or become apparent after a perusal of the following specification and the drawings.

In the drawings:

FIGURE 1 is a plan view of one embodiment of the present invention, showing a key applied thereto;

FIGURE 2 is an exploded diagrammatic perspective view of the device of FIGURE 1;

FIGURE 3 is a view similar to that of FIGURE 1, but illustrating a modification of the invention, parts being broken away; and

FIGURE 4 is a diagrammatic perspective view illustrating still another embodiment of the invention, with the showing being similar to that of FIGURE 2.

Reference numeral 10 of FIGURES 1 and 2 generally indicates one form of the invention which comprises an elongate key receiving element 12 and a keeper device 14 which secures one or more keys 16 on the key receiving element 12.

As made clearly evident by FIGURE 2, the key receiving element 12 comprises a length of resilient wire 17 formed to position its ends 18 adjacent each other with the tips 20 thereof diverging somewhat from each other.

Generally speaking, the ends 18 of the element 12 are disposed substantially parallel to each other, and after the key 16 is applied to the element 12, the keeper device 14 is pressed between the ends 18 to dispose the ends 18 in the pockets 21 that are formed on opposite sides of the device 14. The device 14 is formed and proportioned so that the ends 18 of device 12 will be pressed apart somewhat as the device 14 is pressed within and between ends 18, so that the tips 20 will tend to snap into recesses 23 that are formed in the bottoms of the respective pockets 21.

As is also brought out by FIGURES 1 and 2, the key receiving element 12 is formed with inclined portions 26 against which the thumb and forefinger of one's hand may be applied to hold the element 12 against the compressive forces occasioned by pressing the device 14 between the ends 18.

2

In addition, the ends 18 each are formed to define curved segments 27 that substantially conform to the bottoms of the respective pockets 21. The curved portions 27 merge into and help define the indentations generally indicated at 29, which together with the inclined portions 26 and the rounded end portion 31 define a handle for the element 12.

The keeper device 14 generally comprises a rounded frame member 40 of generally quadrilateral transverse cross-sectional configuration which is substantially C-shaped in configuration and terminates in substantially parallel end portions 42. The frame member 40 is formed with guide or side flanges 44 along the sides of each end thereof that respectively merge into the respective end flanges 46, with these flanges 44 and 46 defining the respective pockets 21. The convexly rounded peripheral exterior surface 48 of the member 40 is continuous between the end flanges 46 and forms the bottoms of the respective pockets 21, with the surface 48 being suitably indented as at 23 to define outwardly opening recesses for the tips 20 of element 12.

As clearly brought out in FIGURE 1, the tips 20 define protuberances 50 that are directed towards each other, and are proportioned to be received in the respective pocket recesses 23.

Journalled between the ends 42 of the member 40 is a novel advertising spinner element, one embodiment of which is diagrammatically illustrated at 52. In the embodiment of FIGURES 1 and 2, the element 52 comprises a disc-like member 54 provided with pins 56 that are positioned at diametrically opposite points about the exterior periphery 58 of the member 54, and that are respectively lodged in suitable openings 60 formed at diametrically opposed points in the member 40. Pins 56 may be applied by making them in tapered form and press fitting them into element 52 through openings 60.

The member 40 and the spinner member 52 have curvatures which substantially complement each other, and the fit between the pins 56 and the holes 60 should be such that the member 54 may be freely rotated. Member 54 is provided with disc-like surfaces 62 on which advertising indicia of any suitable type may be disposed in any suitable manner.

The utility and manner of using the device 10 will now be obvious from what has been said. The element 12 when assembled with the device 14 will be arranged substantially as shown in FIGURE 1, and these two elements may be separated by applying one's forefinger into the bite that is defined by the handle portion 31 of element 12, grasping the device 14 with the other hand (which by its shape forms a handle that is readily grasped by the other hand), and pulling on the element 12 to position these elements somewhat as shown in FIGURE 2, in which condition of element 12 keys 16 may be applied and removed with respect to the element 12.

When the element 12 is assembled on the device 14, the element 12 serves as a handle for holding the device 14 when it is desired to spin the advertising spinner member 52. This may be done by merely flicking member 52 with one's finger.

In the embodiment of FIGURE 3, the spinner member 52a is substantially the same as member 52, but instead of being journalled within the modified member 40a by a pair of diametrically opposed pins 56, the member 52a is journalled within member 40a by a single pin 70 which is formed with a reduced portion 72 that is received in opening 74 of member 40a; the pin 70 includes a headed portion 76 that may be formed after pin 70 is received in opening 74 by peening over the outwardly projecting pin end.

It will therefore be seen that the spin member 52a of FIGURE 3 is mounted for rotation about an axis

which extends substantially parallel to the ends 42a of the frame member 40a. The remainder of the member 40a and element 12 are essentially the same as the corresponding elements 12 and 40 of FIGURES 1 and 2.

In the embodiment of FIGURE 4, the frame member 40 and the element 12 are identical to the corresponding elements 40 and 12 of the embodiment of FIGURE 1. However, the spinner member 52b takes the form of a spherical element 54b that has pins 56 applied to diametrically opposed points on the element 54b for reception in holes 60 of member 40. The element 54b is preferably made from a transparent plastic or glass material and has embedded therein suitable advertising indicia or the like. In accordance with this embodiment of the invention, the element 54b is freely rotated by flicking it with one's finger as described in connection with the embodiment of FIGURES 1 and 2.

Alternately, the spinner member 54b of FIGURE 4 may be journaled within frame member 40 by employing the modification of FIGURE 3.

It will therefore be seen that I have provided an extremely simplified form of key holder which is not only easy to operate, convenient to handle, and inexpensive to make, but which also provides a novel and attractive advertising implement.

The foregoing description and the drawings are given merely to explain and illustrate my invention and the invention is not to be limited thereto, except insofar as the appended claim is so limited, since those skilled in the art who have my disclosure before them will be able to make modifications and variations therein without departing from the scope of the invention.

I claim:

A keyholder comprising an elongated resilient key receiving wire member formed to define a planar open loop having a closed end and an open end, with the end portions of said member being positioned adjacent to but spaced from each other to form said loop open end, said loop being formed by symmetrically formed halves of said member that are joined together at the closed end of said loop, said halves being indented toward each other intermediate the loop ends, with the portions of said halves extending between the indented portions thereof and said loop closed end respectively defining substantially rectilinear segments in said wire member that converge in the direction of said loop closed end, and with the portions of said halves extending between said indented portions and said loop open end defining curved segments in said wire member that are arched away from each other and that have the portions thereof that oppose each other concavely shaped longitudinally of said wire member, with said curved segments respectively merging

into said wire member end portions, said wire member end portions being formed to define protuberances that project toward each other and terminate in tips that diverge from each other, and a keeper device cooperable with said resilient member curved segments and end portions for retaining keys on said key receiving member, said keeper device comprising a frame member having a substantially quadrilateral cross-sectional configuration and formed to define a substantially C-shaped configuration in which the opposing side surfaces of said frame members have a convex-concave relation wherein the convex surface is the outwardly facing peripheral surface of said C-shaped configuration, and the concave surface is the inner surface thereof, said frame member having its end portions extending substantially parallel to each other, said frame member end portions each being formed to define a pair of substantially parallel outwardly projecting side flanges and an end flange extending cross-wise of and connected to the respective side flanges adjacent the tips of said frame member, said peripheral surface of said frame member, said side flanges, and said end flanges defining pockets adjacent said frame member end portions for receiving the respective protuberances of said key receiving member, said side flanges respectively merging into said peripheral surface at points along said frame member on either side of the midportion thereof, said peripheral surface adjacent the respective end flanges being indented to define outwardly opening recesses in said peripheral surface for receiving said key receiving member protuberances, whereby, said key receiving member may be applied to said keeper device by pressing said convex peripheral surface against said key receiving member protuberances to separate and cam the latter into said pocket and into engagement with the respective end flanges, whereupon said protuberances seek said convex surface pockets to latch said keeper device between said key receiving member end portions, said rectilinear segments of said key receiving member serving as finger bracing portions for pressing said key receiving member against said keeper device.
